CLAIM

We claim the ornamental design for a barcode reading module, as shown and described.

DESCRIPTION

FIG. 1 is a front left isometric view of a barcode reading module according to the present invention.

FIG. 2 is a front view of the barcode reading module of FIG. 1.

FIG. 3 is a rear view of the barcode reading module of FIG. 1.

FIG. 4 is a top view of the barcode reading module of FIG. 1.

FIG. 5 is a bottom view of the barcode reading module of FIG. 1.

FIG. 6 is a left side view of the barcode reading module of FIG. 1; and,

FIG. 7 is a right side view of the barcode reading module of FIG. 1.

Broken lines and unshaded portions contained within broken lines depict portions of the barcode reading module that form no part of the claimed design but are shown for purposes of illustration.
